WALL HANGER

Carl-Arne Breger, Torup, Sweden, assignor to Barebo AB, Torup, Sweden

Filed Sept. 22, 1975, Ser. No. 615,400

Term of patent 14 years

Int. Cl. D8—08

U.S. Cl. D8—257

FIG. 3

FIG. 1

FIG. 4

FIG. 2

FIG. 5

FIG. 1 is a rear plan view of my design for a wall hanger;

FIG. 2 is a plan view of the front thereof;

FIG. 3 is a perspective view of my design for a wall hanger lying on its front as viewed obliquely from above;

FIG. 4 is another perspective view thereof lying on its rear surface as viewed from above and from one end;

FIG. 5 is still another perspective view thereof lying on its rear surface as viewed from above and from one end.

I claim:

The ornamental design for a wall hanger, as shown and described.
